UNITED STATES PATENT OFFICE.

HIRAM C. WILLIAMS, OF UTICA, AND STEPHEN R. PAYNE, OF SYRACUSE, NEW YORK,
ASSIGNORS OF ONE-THIRD TO FRANCIS B. HARRINGTON, OF ALBANY, NEW YORK.

AUDIBLE SIGNAL.

1,041,393.

Specification of Letters Patent. Patented Oct. 15, 1912.

Application filed May 11, 1911. Serial No. 626,403.

To all whom it may concern:

Be it known that we, HIRAM C. WILLIAMS and STEPHEN R. PAYNE, citizens of the United States of America, residing, respectively, the said HIRAM C. WILLIAMS at the city of Utica, Oneida county, New York, and the said STEPHEN R. PAYNE at the city of Syracuse, Onondaga county, New York, have invented certain new and useful Improvements in Audible Signals, of which the following is a specification.

Our invention relates to a new and useful improvement in audible signals, and the object of our invention is to provide a device adapted to be connected with a railroad track whereby the passage of a car upon a section where it is not intended to pass will cause an audible signal to sound; together with such elements and combinations as are hereinafter more particularly set forth and claimed. We accomplish this object by means of the mechanism illustrated in the accompanying drawings, in which:

Figure 1 is an elevation. Fig. 2 is a plan showing the semaphore signal registering "clear," with a car on the block section. Fig. 3 is a plan showing the semaphore signal at "danger," with no car on the block section. Fig. 4 is a plan showing the semaphore at "danger" with a car on the block section, the audible signal sounding. Fig. 5 shows the semaphore "clear" with a car on the block section and another one just leaving same.

Similar letters refer to similar parts throughout the several views.

Many accidents have occurred because of the engineer omitting to stop even when the danger signal is displayed. Sometimes this disobedience of signals is the result of carelessness; sometimes the signal is not seen or is misunderstood, and not infrequently it is unheeded intentionally.

The object of the present invention is to cause a shrill penetrating whistle, alarm or other sound which will be readily and distinctly heard above the noise and commotion attendant upon the moving train. This will not only recall to the engineer and occupants of the cab that a signal has been passed; but all of the crew and, indeed, the passengers on the train will be apprised of the fact that the signal is being ignored. We also provide for sounding a signal when the semaphore shows a clear track, provid-

ing there is still a train on the electric track circuit at the time that another train is approaching the same.

The track circuit, A, is composed of the rails, a, b, insulated at c, c, and d, d, from the rails, C, C, and D, D. The track circuit, A, is electrified by means of the battery, 1, connected by wire, e, to the rail, b, and by wire, f, to the rail, a. The magnets, B, G, and H, which may be placed in the relay box, J, Fig. 1, with battery, 2, battery, 3, magnet, L, solenoid, M, and semaphore switch, N, are connected up as follows: The magnet, B, is connected by the wire, E, to the rail, a, and by wire, F, to the rail, b. From the battery, 2, the wire, g, leads to the armature, O, which is so mounted that when the current is passing through the magnet, B, the armature, O, will be drawn toward the magnet and make connections with the wire, h, leading to the magnet, H. But when the current is not passing through the magnet, B, the armature, O, will engage the wire, j, leading to the armature, P, operated by the magnet, G. The armature, P, is connected with the wire, k, leading to the contact, R, with which the semaphore switch, N, is adapted to engage. The wire, k, also connects with the magnet, G, by the wire, m. The battery, 2, is connected with the wire, n, which leads to the magnet, G, and also to the magnet, H, and the wire, p, connects the wire, g, near the battery, 2, with the armature, S, adjacent to the magnet, L. The wire, s, connects the semaphore switch, N, with a contact piece, T, with which the armature, S, engages when operated upon by the magnet, L. The magnet, L, is connected in a track circuit of a section in advance of the section controlling magnet, B. A wire, 4, connects track, D, to magnet, L, and the track, C, is connected with said magnet by means of a wire, 5. The wire, g, has connected with it a wire, V, which leads to the contact, W', with which the armature, W, engages. The other end of the armature, P, is connected by the wire, X, with the wire, h.

The battery, 3, has a wire, 6, which leads to the electromagnet, M, and another wire, 7, leads to the contact, 8, of armature, 9, of the magnet, H, the armature, 9, being also connected by means of the wire, 10, with the electromagnet, M. The electromagnet, M, operates the lever, U, to close the valve, Y,

controlling the whistle or sounding apparatus Z, when the magnet is electrified. A spring, t, is mounted to force the valve, Y, open when the electromagnet, M, is demagnetized. The semaphore, 12, is connected by rod or other suitable connection, 13, with the semaphore switch, N, and is operated in any suitable manner, not shown.

The tank, 15, which may contain gas or compressed air is provided with a pressure governor, 16, which gas or compressed air is controlled in its passage through the pipe, Z', by means of the valve, Y, leading to the megaphone, 17, and is an illustration of the means for sounding an alarm, but is not intended to be a limitation upon our invention because any means for sounding an alarm which is put into operation by substantially the same devices that we have shown, will come within the spirit of our invention.

In Fig. 2 the semaphore signal, 12, shows the track to be clear. 18, represents a locomotive on the track circuit going in the direction of the arrow. We will now follow the circuits in our apparatus when the conditions are those shown in Fig. 2. From the battery, 1, a current passes by wire, f, to rail, a, thence to locomotive, 18, crossing to rail, b, to wire, e, to battery, 1. The magnet, B, has been short circuited by the locomotive, 18. The armature, O, of the magnet, B, therefore rests upon the wire, j. The circuit from the battery, 2, will be by wire, g, wire, p, armature, S, contact, T, to semaphore switch, N, contact, R, wire, h, wire, m, magnet, G, wire n, to the battery. The current from the battery, 2, also passes through wire, g, to wire, V, armature, W, wire, X, wire, h, to magnet, H, to wire, n, to the battery, energizing magnet, H, and closing armature, 9, and places in circuit with battery, 3, the electromagnet, M, which holds the valve, Y, in position in the pipe, Z, preventing the sounding of the signal. The magnet, L, acts upon the armature, S, keeping it closed because of the battery, 20, connecting the tracks, C and D, beyond the track circuit, A. It will thus be seen that the track being clear and the semaphore signal showing it to be clear, there is no signal sounded when the locomotive, 18, is on the track circuit.

In Fig. 3, we show the semaphore signal, 12, at danger, which opens the connection between the contact, R, and the armature, S, because of the opening of the semaphore switch, N. The locomotive, 18, not being in the track circuit the battery, 1, sends a current through the magnet, B, and closes the armature, O, and the armatures, P and W, are open because the switch, N, is open and the current from battery, 2, passes to magnet, H, picks up the armature, 9, and passes by means of wire, h, armature, O, and wire, g, back to battery, 2. Thus the

electromagnet, M, will be charged and the whistle not be sounded.

In Fig. 4 we show the signal at danger and the locomotive, 18, on the track circuit, in violation of the semaphore signal, and the audible signal is sounded. In this case the locomotive, 18, short circuits the magnet, B, and the semaphore opens the semaphore switch, N. Therefore the electromagnet, M, is not energized and the spring, t, opens the valve, Y, and allows the contents of the tank, 15, to escape upon the sounding of the whistle or signal.

In Fig. 5 we show the semaphore signal clear with the locomotive, 18, on the track circuit and a locomotive, 19, having just left the track circuit. The whistle or signal is now sounded for the reason that the locomotive, 19, short circuits the magnet, L, which breaks the connection between the contact, T, and armature, S, which prevents the magnet, G, from being charged by battery, 2, and therefore allows the armatures, P and W, to break connection with their respective contact points, and the locomotive, 18, short circuiting the magnet, B, the magnet, H, is prevented from being magnetized, whereby the electromagnet, M, is demagnetized and the valve, Y, opens.

We do not wish to be limited to the wiring or electrical connections illustrated, nor to the means for making an audible signal, because these devices may be changed and diversified without departing from the spirit of our invention.

Where we have referred to locomotive, 18, we of course mean to include, beside the locomotive, all the cars that are attached thereto.

It is apparent that the audible signal will continue to sound as long as the train is passing over the track section, contrary to the requirements shown by the semaphore.

What we claim as our invention and desire to secure by Letters Patent is:

1. A track divided into blocks; a semaphore signal and an audible signal; electromagnetic means controlling said audible signal; means controlled by the presence of a train on the block adjacent said signals for closing a circuit through said electromagnetic means when the block is clear; means controlled by the semaphore and the presence of a train on the block in advance for closing another circuit through said electromagnetic means when the semaphore is at clear and the block in advance is unoccupied, and to break said circuit when either the signal is at danger or the block in advance is occupied, whereby the electromagnetic means will be deenergized to sound the audible signal when a train is on the first mentioned block section and the signal is at danger or the signal is at clear and the block section in advance is occupied.

2. A track divided into blocks; an audible signal; electromagnetic means controlling said audible signal; means controlled by the presence of a train on the block adjacent to said signal for closing a circuit through said electromagnetic means when the block is clear; means controlled by the presence of a train on the block in advance for closing another circuit through said electromagnetic means when the block in advance is unoccupied, and to break said circuit when the block in advance is occupied, whereby the electromagnetic means will be deenergized.

to sound the audible signal when a train is on the first mentioned block section and the 15 block section in advance is occupied.

In testimony whereof we have affixed our signatures in presence of two witnesses.
